UNITED STATES PATENT OFFICE

136,510

DESIGN FOR A FENDER FOR JUVENILE VEHICLES

William I. Smith, Goshen, Ind., assignor to The Hettrick Manufacturing Company, Toledo, Ohio, a corporation of Ohio

Application January 20, 1943, Serial No. 109,287

Term of patent 7 years

To all whom it may concern:

Be it known that I, William I. Smith, a citizen of the United States, and a resident of Goshen, Elkhart County, Indiana, have invented a new, original, and ornamental Design for a Fender for Juvenile Vehicles, of which the following is a specification, reference being had to the accompanying drawing, forming a part thereof.

In the drawing:

Figure 1 is an inside perspective view of a

fender for juvenile vehicles, showing my new design;

Figure 2 is an outside perspective view;
Figure 3 is a top plan view; and
Figure 4 is an inside elevational view thereof.
I claim:

The ornamental design for a fender for juvenile vehicles, as shown.

WILLIAM I. SMITH.
